KEY MECHANISM FOR WOODWIND INSTRUMENTS

Ford D. Platz, Fort Wayne, Ind., assignor to C. G. Conn, Ltd., Elkhart, Ind., a corporation of Indiana

Application May 2, 1936, Serial No. 77,491

8 Claims. (Cl. 84—382)

This invention relates to woodwind musical instruments, and is illustrated as embodied in a clarinet.

The principal object of this invention is to provide improved means for prolonging the utility of key mechanism for woodwind musical instruments.

Another object is to provide coacting spring and non-metallic means for the elimination of noise and the prolongation of the utility and efficiency of certain clarinet key mechanism.

In the instrument illustrated, the invention is utilized to improve the action of a thrust device through which one of the keys, which is pivoted on one shaft, is operated by an arm on a different shaft.

Other and more specific objects of the invention are mentioned and described herein.

The invention is illustrated in the accompanying drawing, wherein

Figure 1 illustrates a fragment of the upper branch of a seven ring Boehm clarinet in which the invention is incorporated;

Figure 2 illustrates the same clarinet section but rotated at approximately right angles;

Figure 3 illustrates a section taken on line 3—3 of Figure 1; and

Figure 4 illustrates a similar fragmental section taken on line 4—4 of Figure 2, much enlarged.

Similar numerals of reference indicate like parts throughout the several views on the drawing.

Referring to the details of the drawing the numeral 1 indicates one section of a tubular clarinet body which is provided with the usual reduced portion 2 for telescopically connecting it with an adjacent section (not shown) as is well known in the art. The numeral 3 indicates the B key which is rigidly carried upon the outer end of the tiltable key arm 4 rigidly connected with the rock shaft 5, the opposite ends of said rock shaft being journaled in the posts 6 and 7 which are fixed in the body 1. Normally, the B key 3, which is adapted to close the tone hole 8 when depressed, is raised by a spring (not shown) as indicated in Figures 3 and 4, as is well known in the art.

The posts 6 and 7 carry a second rock-shaft 9 which is arranged parallel with and above the shaft 5 and adjacent thereto, said shaft 9 carrying a laterally projecting arm 10 rigid therewith and arranged above the B key arm 4 and tilttable toward the latter. The shaft 5 carries also the laterally projecting arm 12 on which the A ring-

key 11 is mounted, and upon depression of the latter the key 3 is actuated to close the tone hole 8. The shaft 9 carries the laterally projecting arm 13 on which the B flat ring-key 14 is mounted and by which the shaft 9 may be rocked, and when thus rocked the arm 10 tilts the arm 4 inwardly, thereby causing the key 3 to close the tone hole 8. The shaft 9 may also be rocked by the arm 15 which carries the bridge element 16 when the latter is lifted by a coacting lever element (not shown) but which is mounted upon the adjacent clarinet section, as is well known in the art.

The upper edge of the B key arm 4 carries a thin strip of cork, or other suitable non-metallic material, indicated by the numeral 17. This strip may be adhesively secured to the key arm. According to the present invention, said cork strip is coacting with a flat leaf spring 18 which is fastened to the under surface of the arm 10 in any suitable manner, as, for example, by the screw 19. Adjustment of the spring 18 toward the cork strip 17 is necessary, due to irregularities in the parts, to maintain the contact thereof, this adjustment being effected by the adjusting screw 20 which is mounted in the semi spherical head 21 of the arm 10. The adjustment of the screw 20 may be maintained by a set screw 22 which is also mounted in the head 21.

When the B key arm 4 is tilted by the depression of the arm 10 to cause the closure of the tone hole 8, as described, and when both arms 4 and 10 are retracted by spring action, there is a constant "wiping", or frictional, contact between the flat spring 18 and the cork strip 17, whereby noise is eliminated and wear on the cork strip is negligible, thereby prolonging the utility of the latter indefinitely.

While one illustrative embodiment has been described in detail, it is not my intention to limit the scope of the invention to that particular embodiment, or otherwise than by the terms of the appended claims.

I claim:

1. In a woodwind musical instrument, a movable key arm, a second movable arm arranged adjacent said key arm and adapted to actuate the latter, and coacting metallic and non-metallic elements carried respectively by said arms, the metallic element being of resilient material and having a part urged yieldingly away from the arm which carries it and held constantly in engagement with the non-metallic element.

2. In a woodwind musical instrument, a movable key arm, a second movable arm arranged

adjacent said key arm and adapted to actuate the latter, and coacting metallic and non-metallic elements carried respectively by said arms, said metallic element being a resilient leaf spring having one end secured to the arm which carries it and having its other end yieldingly urged into engagement with the non-metallic element.

3. In a woodwind musical instrument, a movable key arm, a second movable arm arranged adjacent said key arm and adapted to actuate the latter, and coacting metallic and non-metallic elements carried by said arms respectively, and means for adjusting the position of the metallic element upon the arm which carries it, said metallic element comprising a member extending along and secured at one end to the arm which carries it and the other end of which can be moved away from said arm by adjusting said means.

4. In a woodwind musical instrument, a tilt-able key arm, a second tilttable arm arranged above said key arm and adapted to actuate the latter, and coacting metallic and non-metallic elements carried by said arms, said metallic element being a resilient member extending along the arm and secured thereto at one point and in wiping engagement with the non-metallic element, the arm carrying the resilient metallic element having an adjustable thrust member in supporting engagement therewith.

5. In a woodwind musical instrument, a tilt-able key arm, a second tilttable arm arranged above said key arm and adapted to actuate the latter, one of said arms having a flat metal ele-

ment secured at one of its ends to the arm and which is engageable adjacent its free end with the other arm, and said one arm having means engaging said element adjacent its free end and which is adjustable to vary the spacing between 5 said free end and said one arm.

6. In a woodwind musical instrument, a tilt-able key arm, a second tilttable arm arranged above said key arm and adapted to actuate the latter, and a flat resilient metallic element adjustably carried by one of said arms and secured thereto at one end, in position to engage the other of said arms, said one arm having means for springing the free end of said element more or less toward the other arm to adjust it. 15

7. In a woodwind musical instrument, a tilt-able key arm, a second tilttable arm arranged above said key arm and adapted to actuate the latter, an adjustable element carried by one of said arms, and a leaf spring secured to said one 20 arm at its end and supported by said element and arranged to engage the other of said arms.

8. In a woodwind musical instrument, a tilt-able key arm carried on a rockshaft, a second tilttable arm carried on a second rockshaft and 25 arranged above said key arm, said second tilttable arm being adapted to tilt said key arm, a resilient metallic element carried by said second arm, and having one part fixedly secured thereto, and screw means carried by said second 30 arm and engaging another part of said element for adjusting said metallic element.

FORD D. PLATZ.
